ADDED THREAD-FEEDING ATTACHMENT
FOR CIRCULAR KNITTING MACHINESClayton A. Fenstermacher, Reading, Pa., assignor
to Schuylkill Hosiery Mills, Inc., Reading, Pa.,
a corporation of Pennsylvania

Application December 11, 1936, Serial No. 115,337

13 Claims. (CL. 66—133)

This invention relates to circular knitting machines, and more particularly to a new and improved pattern-controlled guide-feeding attachment for introducing into selected courses during the knitting of a stocking or the like formed of a main or body thread or threads, of an added thread or strand, preferably, for present purpose, of an elastic nature to form a garter area in the finished product; the primary object of the present improvements being to provide a guide feed for such elastic strand that may be applied to a knitting machine equipped for producing known true-wrap vertical stripes or like ornamental designs of added embroidery thread or yarn.

In producing such true-wrap vertical stripes, the guides for the embroidery threads ordinarily overhang the circle of needles with their threads floating downwardly therefrom to their loop engagements in the knit fabric, and such depending floats have heretofore been recognized as preventing adding such elastic thread or strand desirably introduced into spaced courses of the main knitting due to entanglement of the elastic floats with such embroidery thread floats.

It is therefore an essential requirement, and one of the objects of the present improvements, to provide for feeding the elastic thread to the desired spaced courses with the necessary floats between such courses held and maintained out of contact and free from entanglement with the striping threads, or any other main, or changed, or added thread or yarn ordinarily required or desirable to feed to the knitting needles.

Another object is to feed the elastic thread or strand under a controlled tension and preferably to spaced ones only of the needles in each engaged course, so that retraction of the stretched elastic thread will draw together the engaged wales and effect a rib-like appearance of the plain-knit fabrics in such garter portion.

Other objects and advantages resulting in a novel and improved stocking construction will appear in connection with the following specification describing in detail and in connection with the accompanying drawings forming part thereof, the nature of the present improvements and the manner and method of operating the same to produce the desired stocking or like-knit tubular fabric.

Referring to the accompanying drawings which disclose a preferred embodiment of the present improvements in connection with a circular knitting machine having a known striping attachment such as that shown in Robinson United

States Letters Patent No. 1,428,398 of September 5, 1922, and No. 1,864,321 of June 21, 1932.

Fig. 1 is mainly a side elevation, largely diagrammatic, and partly in vertical section, showing essential portions of a usual knitting machine having a striping attachment, and indicating a preferred embodiment of the present improvements applied thereto.

Fig. 2 is an enlarged cross-sectional view taken substantially on the line 2—2 of Fig. 1, showing the feeding position for the rubber thread guide.

Fig. 3 is a side elevation of the parts shown in Fig. 2.

Fig. 4 is a cross-sectional view similar to that shown in Fig. 2, but indicating the rubber thread guide in non-feeding position.

Fig. 5 is a conventional flat folded side view of a stocking indicating diagrammatically the application thereto of the present improvements.

The present invention may be applied to any usual type of circular knitting machine, and the one shown in the drawings embodies the main functional elements of the known Banner machine more fully shown and described in Lawson United States Patent No. 933,443 of September 7, 1909, as reference thereto will appear, and the construction and knitting operation of which is well understood and needs no detailed description for a full understanding of the present invention.

Parts of such known machine indicated in the drawings, include the usual frame or stand 1; needle cylinder 2; circle of needle 3, in this case provided with butted jacks 4 for added operation as later herein described; pattern drum shaft 5; and a drive gear 6 of the nature of gear i' of the train of gears of said Lawson patent, rotating in the present instance as in said patent, one revolution to four revolutions of the needle cylinder 2. This machine, as heretofore, produces a stocking by knitting a main thread or threads in a succession of circular courses and vertical wales as well understood and needing no further showing or description.

The striping attachment indicated as an attachment to the above machine is of the nature more fully described in the aforesaid Robinson patents, essential parts only being shown, and the operation of forming vertical stripes interknit with the stocking by wrapping embroidery threads around certain needles or groups of needles is as heretofore and fully described in detail in said Robinson patents as reference thereto will disclose.

Parts of such known Robinson striping attachment indicated in the drawings include, a frame-carried standard 10, having an upper arm 11 supporting a depending shaft 12 centrally suspended over the needle cylinder 2. A sleeve shaft 15 on shaft 12 supports a bobbin table 16 and table 17 for thread guiding and tensioning means, not shown, and said tables are rotated in synchronization with needle cylinder 2 by vertical shaft 18 suitably geared to the knitting machine drive mechanism and to table 16 as in said Robinson patents. A series of thread guide fingers 20 for the striping threads are pivotally mounted in notches 21 in a disc 22 mounted on shaft 12 and rotated with tables 16 and 17 by means of a bracket 23 secured to table 17 engaging a bracket 24 secured to disc 22. A cam disc 25 operates the fingers 20 as set forth in said Robinson patent to swing them radially across the circle of needles 3, and their thread carrying ends 26 are swung circumferentially of said circle of needles as reference to said Robinson patent will more fully describe. And the jacks 4, controlled from the pattern drum 27 on shaft 5, through levers 28 operate as heretofore to raise the desired needles into feeding position to receive the threads fed to and wrapped around them by the guide fingers 20.

The mechanisms above briefly described and indicated in the drawings, will produce, as fully set forth in said referred to patents and well known in the art, knitted stockings having vertical true wrap stripes, pattern figures, clocks, and the like in certain wales formed by the embroidery threads fed by the guide fingers 20 to the needles determined by the pattern controlled selective action of the jacks 4. And such embroidery threads will float downwardly from their guides to their last engaged interknit looping in the main fabric. This floating extension of these embroidery threads will interfere with any usual feed of a continuous thread or yarn to the needles to form spaced courses of such added thread, as it will be readily seen that the floats for the last engaged loop to any usual guide as one of the guide *d'* of said Lawson Patent No. 933,443, would, during the needle cylinder rotation, extended across the latter and become entangled with the embroidery threads as will be clearly understood.

The present improvements provide means for feeding added thread to be engaged and interknit preferably in spaced circular courses, with the floats of said thread between said courses, held out of possible entanglement with the above described embroidery threads, and the particular embodiment of such means shown in the drawings will now be described in detail.

The thread 30 indicated is preferably of a highly elastic nature such as "latex" or a like thread formed of a pure rubber strand or one having a known gimp covered rubber core, so as to have a garter action and support the stocking on the leg of the wearer, and this thread 30 is shown as fed from a suitable supply cone or bobbin 31 through tensioning means 32 to a guide finger 33 movable into feeding and non-feeding position relative to the circle of needles 3.

An arm 35 (Fig. 1) suitably supported above the frame table, fixedly carries a ring plate 36 encircling the disc 22 in which the guide fingers 20 are pivotally mounted, said ring acting as a guide bearing for said disc which is free to rotate therein. The plate 36 is shown as recessed to receive a rotatable ring or annulus 38, retained as by cleo fingers 39, this ring also encircling disc

22 and is intermittently rotated with the latter as will later herein appear.

Ring 38 has mounted thereon an arm 40 carrying bobbin 31 so the latter will travel or rotate with said ring, and guide finger 33 for thread 30 is carried by said ring, being secured in one end of a plate 41 pivoted centrally at 42 to ring 38 and movable thereon to position finger 33 in feeding position within a recess 43 formed in ring 38 (Fig. 2), or to non-feeding position in a recess 10 or notch 44 in disc 22 (Fig. 4), the drawings showing a stop member 45 in said notch to limit the movement of the guide finger. The guide finger 33 when in notch 43 of ring 38 is held non-rotatable with said ring, as will later herein appear, 15 and its lower end will be then positioned outside the circle of needles 3 (Fig. 1) which latter in the present construction are rotating, and the needles, raised by the aforesaid pattern controlled jack means, will receive the thread 30. When 20 guide finger 33 is moved into notch 44 of disc 22, its lower end will be inside the circle of needles 3, and finger 33 and ring 38 will then rotate with disc 22, positioning the float of thread 30 in a midway vertical position between embroidery 25 threads fed by striping fingers 20, where it will be out of any danger of entanglement with the latter.

To hold the finger 33 in engaging position with notch 44, and to insure rotation of ring 38 with disc 22 when the finger is so engaged, the drawings show a notched plate 46 on disc plate 22, engageable by a catch plate 47, pivoted at 48 to ring 38. Plate 41 is shown as actuated by a spring 50 to normally tend to move finger 33 into notch 44; and to move said finger reversely to the position shown in Fig. 2, the drawings show a vertically movable strike finger 51 mounted in a slide bearing 52 secured to ring plate 38 and tensioned by spring 53 to normally project said finger 51 upward into the path of travel of plate 41 when ring 38 is rotated. The end 54 of plate 41 is cam-shaped, as shown, so that contact therewith of finger 51, acts to turn said plate on its pivot 42 and move guide 33 from recess 44 of disc 22 into recess 43 of ring 38, as shown in Fig. 2. Plate 41 is shown with a notch 55 to receive pivot post 48 and permit this movement of the plate. The raised strike finger 51 also engages the hooked end 56 of catch plate 47 and turns the latter on its pivot 48 to withdraw its opposite end from notched plate 46 on disc 22; a latch 57 pivoted at 58 to catch plate 47 and tensioned by spring arm 59 engaging and holding against back lash the raised strike finger 51 in the hooked end 56 of catch plate 47. The parts are now in the position indicated in Fig. 2, and ring 38 is held at rest in ring 38, which is the thread feeding position for finger 33, while disc 22 rotates.

It will be seen from the above detailed description in connection with the drawings, that when strike finger 51 is in raised position, finger 33 will be moved and held outside the rotating circle of needles 3 so as to feed its thread to raised needles selected by jacks 4; and that when finger 51 is lowered, spring 50 will act to position guide finger 33 in non-feeding position in disc recess 44, and catch plate 47 will engage notched plate 46 to cause ring 38 to rotate with disc 22. In this position guide 33 depends idly within the circle of needles 3 between two striping thread guides 20, 20, and thread 30 will remain in non-entangling position between the threads fed by said guides 20, 20. And it is evident that by moving strike 75

5 finger 51, feed of the thread 30 to desired courses may be controlled, and that automatic control of said finger movement may be determined by the machine pattern mechanisms as will now be set forth.

10 It is clear that by utilizing one of the levers 28, or an additional one for this particular purpose, selected jacks may be operated to raise their needles into a position to receive the thread 30 from guide finger 33 when the latter is moved to feeding position, Fig. 2; and in Fig. 3 certain needles 3a are shown raised for this purpose, which needles may be every fourth one, as indicated or another selected arrangement. And to 15 move strike finger 51, the drawings show an angular extension 60 from the lower end of said finger engaged by an arm 61 at an end of rock shaft 62, the connection of arm 61 to extension 60 being provided by a stud screw 63 in the latter engaging an elongated aperture 64 in arm 61. Rock shaft 62 is shown as mounted in bearing 65 secured to ring plate 36 and an extension 66 from standard 10, and the opposite end of shaft 62 is provided with a crank arm 67. A link rod 70 20 (Fig. 1) connects cam arm 67 to the end of a lever 71 centrally pivoted at 72 to frame 1 and its other end 73 riding on a cam disc 74 mounted upon and rotating with pattern shaft 5. The connection of link rod 70 to end of lever 71 is by 25 means of a pin 75 of said lever engaging in a slotted aperture 76 in link rod 70 so the latter may have imparted thereto a movement other than by said lever 71. The bearing surface of cam disc 74 is shaped to operate the lever at the proper time to rock shaft 62 and lower strike finger 51 out of engagement with latch 57 and the hooked end 56 of catch plate 41 permitting spring 50 to swing plate 41 on its pivot 42 to move guide finger 33 from recess 43 in ring 38 30 (Fig. 2) to position in recess 44 in disc 22 (Fig. 4), this latter position being the normal position for finger 33, except in such portion of the fabric it is desired to add thread 30.

When feed of thread 30 is desired, a suitable 45 low portion, as 77 of cam disc 74 permits lever 71 to turn freeing rock shaft 62 to turn, under tension of spring 53 of finger 51 and a spring 78 connecting link rod 70 to frame 1, and this rocking of shaft 62 will cause finger 51 to rise into 50 the path of travel and engage the cam end 54 of plate 41 rotating with ring 38. In order to feed the thread 30 to spaced courses of the knitting without complicated construction of the cam surface of disc 74, the drawings show provision 55 for additionally rocking shaft 62 at desired intervals while lever end 73 is riding in low portion 77 of cam 74. Every fourth course is a desirable spacing for the feeding of the thread 30, and advantage is taken of the known ratio of travel 60 of gear 6 once to four rotations of needle cylinder 2, said gear being shown with a side cam track 80 engaged by an anti-friction roller 81 on a crank arm 82 of a rock shaft 83, an arm 84 on said shaft extending across link rod 70 and 65 engageable with a stud pin 85 on the latter to raise said rod 70 at each rotation of gear 6, slot 76 in the lower end of rod 70 permitting this movement when lever end 73 is engaging low portion 77 of cam disc 74. This movement of link 70 rod 70 at each fourth rotation of the needle cylinder 2, will rock shaft 62 to raise finger 51 to act on plate 41 and move guide finger 33 to feeding position; said finger 51 being lowered at the 75 end of a needle cylinder revolution and remaining lowered during the next three cylinder rota-

tions until gear cam 80 again causes rock shaft 83 to raise rod 70.

Fig. 5 is a conventional showing of a stocking of usual plain knitting and is shown as having a series of vertical true wrap stripes 90 plated thereon with embroidery thread wrapped about selected needles by striping guide fingers 20 in the manner set forth in said Robinson patents heretofore referred to. The upper end 91 of this stocking is shown as having the elastic thread 30 10 interknit therewith on every fourth needle and in every fourth course, such elastic thread feed under tension as described causing the engaged wales to draw together giving a rib-knit appearance to the plain knitting producing this top. Horizontal stripes may be introduced into the stocking by change feed of thread or yarn by the usual main thread guide fingers in known manner.

From the foregoing description it is believed 20 that the nature of the present improvements will be fully understood and the main object accomplished by introducing an added thread, preferably elastic as described to a portion of the stocking to form a garter portion, such feed 25 being accomplished in a stocking having true wrap vertical stripes ordinarily preventing the feed of such elastic thread, and that the elastic thread as introduced in the manner set forth will produce a stocking top having the appearance 30 of a usual rib-knitted fabric though actually being of plain knitting.

While described as applied to a specific knitting machine having a known striping attachment, it will be apparent it may be applied to other known 35 knitting machines and that the specific details set forth are intended as illustrations of a preferred embodiment and changes and modification may be made without departing from the invention as defined in the following claims. 40

What I claim is:

1. In a knitting machine having a circle of needles and a relatively fixed striping thread carrier operatively mounted above the latter, a guide finger for an added thread mounted to move 45 radially across the circle of needles, means including a swingable plate mounted on said carrier ring for moving said finger independently of said striping thread carrier to a non-feeding position inside said circle of needles, and to a position 50 outside the latter in feeding relation to all the needles of said circle, there being a fixed relation between said guide finger and needles when said guide finger is in non-feeding position, and a relation of relative rotation between 55 said needles and guide finger when the latter is in feeding position.

2. In a knitting machine having a rotatable circle of needles and a striping-thread carrier mounted above and rotatable with said needles, 60 a guide finger for an added thread mounted to move radially across the circle of needles, swingable finger-supporting means for moving said finger to a non-feeding position inside of and rotatable with said needles and striping thread, 65 carrier, and means for moving said finger to a non-rotatable position relative to said striping thread carrier and needle circle and outside the latter in feeding relation to the latter.

3. In a knitting machine having a rotated circle 70 of needles and a striping-thread carrier mounted above and rotatable with said needles, a guide finger for an added thread radially movable across the circle of needles and having a carrier therefor mounted adjacent said striping-thread 75

carrier, means for moving said guide finger to a non-feeding position inside the circle of needles and to rotatably engage said finger carrier and striping-thread carrier, and means for moving 5 said finger to a fixed feeding position outside said rotated circle of needles in feeding rotation to the latter.

4. In a knitting machine having a rotated circle of needles and a striping-thread carrier mounted 10 above and rotatable with said needles, a guide finger for an added thread suspended above and radially movable across the circle of needles, a rotatable carrier ring for said guide finger enclosing said striping-thread carrier, means for moving 15 said guide finger to a non-feeding position radially inside said circle of needles and for rotatably engaging said finger carrying ring and striping-thread carrier, and means for moving said guide finger to a feeding position outside said circle of needles in feeding relation to the latter and for disengaging said finger carrying ring 20 from rotary engagement with said striping-thread carrier.

5. In combination with a knitting machine having a rotated circle of needles and a striping-thread attachment having a carrier for the striping-thread guide fingers mounted above and rotatable with said needles, means for feeding an added thread to said needles comprising, a fixed bearing above said needles, a ring rotatably carried therein, a plate pivotally secured to said ring and carrying a guide finger for the added thread overhanging and radially movable across the circle of needles, means for moving said plate to rotatably engage said ring with said striping-finger carrier and to non-feedingly position said added thread guide finger inside the needle circle, and means for moving said plate to disengage said ring from said striping thread carrier and for 30 positioning said added thread guide finger in fixed position outside the needle circle in feeding relation to the latter.

6. In combination with a knitting machine having a rotated circle of knitting needles and a striping-thread attachment having a carrier for the striping-thread guide fingers mounted above and rotatable with said needles, means for feeding an added thread to said needles comprising, a fixed bearing above said needles, a ring rotatably carried therein, a plate pivotally secured to said ring and carrying a guide finger for the added thread overhanging and radially movable across the circle of needles, means for normally moving said plate to swing its guide finger to a non-feeding position inside the circle of needles and to rotatably engage said ring with said striping-finger carrier, and means for intermittently moving said plate to disengage said ring from said striping finger carrier and to swing said guide finger to a fixed position outside the needle circle 50 and in feeding relation to the latter.

7. In the construction set forth in claim 6, locking means for retainingly holding said plate in its engaged and disengaged positions relative to said striping-finger carrier.

8. In combination with a knitting machine having a rotated circle of knitting needles and a striping-thread attachment having a carrier for the striping-thread guide fingers mounted above and rotatable with said needles, means for feeding an added thread to said needles comprising, a fixed bearing above said needles, a ring rotatably carried therein, a plate pivotally secured

to said ring and carrying a guide finger for the added thread overhanging and radially movable across the circle of needles, means for normally moving said plate to swing its guide finger to a non-feeding position inside the circle of needles 5 and to rotatably engage said ring with said striping finger carrier, and a pattern-controlled strike finger intermittently operated for moving said plate to disengage said ring from said striping finger carrier and for swinging said guide finger 10 to a fixed position outside the needle circle and in feeding relation to the latter.

9. In the construction set forth in claim 8, a knitting machine drive gear having means for actuating the plate engaging movements of said 15 strike finger, and a pattern-control mechanism for determining the operation of said drive gear means.

10. In a knitting machine having a rotated circle of knitting needles and a striping attachment for wrapping embroidery threads around selected needles, means for feeding an added elastic garter thread to be interknit in selected courses comprising, a guide finger for the elastic thread mounted to overhang and radially move 25 across the circle of needles, and pattern controlled means for moving said guide fingers to non-feeding position inside the circle of needles and for rotating said finger with said needle, and means for moving said guide finger to a position outside 30 said circle of needles in fixed feeding relation to the rotating needle circle.

11. In a knitting machine having a rotated circle of knitting needles and a striping attachment for wrapping embroidery threads around 35 selected needles, means for feeding an added elastic garter thread to be interknit in selected courses comprising, a guide finger for the elastic thread mounted to over-hang and radially move 40 across the circle of needles; biased means for moving said guide to non-feeding position inside the circle of needles and for rotating it with the latter, a knitting machine drive gear operative for intermittently moving said guide to a position outside of said circle of needles in fixed feeding 45 relation to the rotating needle cylinder, and a pattern drum mechanism controlling the operations of said drive gear.

12. In a knitting machine having a rotated circle of knitting needles, and a striping attachment having means for raising selected needles to a feeding position and wrapping embroidery thread around the same, means for feeding an added elastic garter thread to be interknit in spaced wales of spaced courses comprising, a guide finger for the elastic thread mounted to over swing radially across the circle of needles and normally rotated in non-feeding position inside the latter, pattern-controlled means for raising spaced needles into position to receive 60 said elastic thread, and pattern-controlled mechanism operative during certain spaced rotations of the needle cylinder for moving said elastic guide finger to a position outside the circle of needles in fixed feeding relation to the spaced 65 raised needles of the rotating circle.

13. In the construction set forth in claim 12, an elastic thread supply bobbin mounted to rotate with its guide finger, and a tensioning device for said elastic thread positioned between 70 said supply bobbin and said guide finger.
